US00D826913S

(12) **United States Design Patent** (10) Patent No.: **US D826,913 S**
(45) Date of Patent: **** Aug. 28, 2018**

(54) **STAND FOR TV RECEIVER**

(71) Applicant: **LG ELECTRONICS INC.**, Seoul (KR)

(72) Inventors: **Hyunbyung Cha**, Seoul (KR); **Yoonkyeong Lee**, Seoul (KR); **Youngwon Jeong**, Seoul (KR); **Byungmu Huh**, Seoul (KR)

(73) Assignee: **LG ELECTRONICS INC.**, Seoul (KR)

(**) Term: **15 Years**

(21) Appl. No.: **35/502,975**

(22) Filed: **Nov. 8, 2016**

(80) **Hague Agreement Data**

Int. Filing Date: **Nov. 8, 2016**

Int. Reg. No.: **DM/093433**

Int. Reg. Date: **Nov. 8, 2016**

Int. Reg. Pub. Date: **May 12, 2017**

(30) **Foreign Application Priority Data**

May 16, 2016 (KR) 30-2016-0023217

(51) **LOC (11) Cl.** **14-03**

(52) **U.S. Cl.**

USPC **D14/239**

(58) **Field of Classification Search**
